[57] CLAIM

The ornamental design of a drainage instrument for draining bodily fluids, as shown and described.

DESCRIPTION

FIG. 1 is a front and right side perspective view of a drainage instrument for draining bodily fluids showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top and right side perspective view of a second embodiment showing our new design, with the drainage cavity being shown detached;

FIG. 9 is a top and right side perspective view, the drainage cavity attached;

FIG. 10 is a top plan view thereof; and,

FIG. 11 is a bottom plan view thereof.
